DESIGN FOR A STUDY LAMP

Edward Kanter, Cleveland Heights, Ohio, assignor to Railley Corporation, a corporation of Ohio

Application December 29, 1936, Serial No. 66,785

Term of patent 7 years

To all whom it may concern:

Be it known that I, Edward Kanter, a citizen of the United States, residing at Cleveland Heights, in the county of Cuyahoga and State of Ohio, have invented a new, original, and ornamental Design for a Study Lamp, of which the following is a specification, reference being had to the accompanying drawing, forming part thereof, wherein the single figure is a perspective view of a study lamp embodying my new design.

The dominant feature of my design resides in the pedestal therefor.

I claim:

The ornamental design for a study lamp substantially as shown and described.

EDWARD KANTER.
